CLAIM

The ornamental design for a football helmet, as shown and described.

DESCRIPTION

FIG. 1 is a left front perspective view of a football helmet, showing our new design.

FIG. 2 is a left rear perspective view of a football helmet, showing our new design.

FIG. 3 is a front view of a football helmet, showing our new design.

FIG. 4 is a rear view of a football helmet, showing our new design.

FIG. 5 is a left side view of a football helmet, showing our new design.

FIG. 6 is a right side view of a football helmet, showing our new design.

FIG. 7 is a top view of a football helmet, showing our new design; and,

FIG. 8 is a bottom view of a football helmet, showing our new design.

The broken lines illustrate portions of the article that form no part of the claimed design.

1 Claim, 8 Drawing Sheets
